United States Patent Office.

LEVI B. TYNG, OF LOWELL, MASSACHUSETTS.

Letters Patent No. 74,866, dated February 25, 1868.

IMPROVED SKATE.

The Schedule referred to in these Letters Patent and making part of the same.

TO ALL WHOM IT MAY CONCERN:

Be it known that I, LEVI B. TYNG, of Lowell, in the county of Middlesex, and State of Massachusetts, have invented new and useful Improvements in Spring-Skates; and I do hereby declare that the following is a full and exact description thereof, reference being had to the accompanying drawings, and to the letters of reference marked thereon.

To enable others skilled in the art to make and use my invention, I will proceed to describe its construction and operation.

Figure 1 represents a plan of a skate with my improvement attached.

Figure 2 represents a side elevation of the same.

Figure 3 represents a longitudinal section through A and B of fig. 1.

a represents the stock, *b* the runner, *c c* the stands, *d d* the slots, *e e* the spring-seats, and *f f* the springs. The stock *a* is made of wood or any other material, formed and finished with holes near each end. The stands *c c* are made with the screws *i i* cast in, and grooved the thickness of the runner. Through these stands *c c* are holes made for the reception of the screws *n n*. The screws *i i* in the stands *c c* are then placed in the holes in the stock *a*, and secured by means of the nuts *m m*. The runner *b* is made in the usual way, with two or more projections *j j*, their length corresponding with the diameter of the spring-seats *e e*, and length of the stands *c c*. In each of these projections *j j* the slots *d d* are made, the distance between corresponding exactly with the distance between the screw-holes in the stands *c c*. Also on these projections *j j* the spring-seats *e e* are placed. The springs *f f* made of rubber or any other material, of any form or shape, are then placed on the stock so as to come directly over the spring-seats *e e*. The runner *b* is then placed in position in the stands *c c*, the spring-seats *e e* coming directly over and on the springs *f f*, and is pressed down. The screws *n n* are then inserted through the holes in the stands *c c* and slots *d d* in the runner *b*, which securely holds and fastens them in.

The advantage of this simple device and improvement is apparent, there being just sufficient elasticity and spring to the skate, at all times and under all circumstances, to completely and entirely overcome the rigidity, imperfect and uneven surface of the ice; thus the skater is enabled to glide over the ice with more ease and comfort than on the ordinary spring-skates.

What I claim as my invention, and desire to secure by Letters Patent, is—

The combination and arrangement of the grooved stands *c c*, slots *d d*, screws or pins *n n*, spring-seats *e e*, and springs *f f*, substantially as and for the purpose herein specified.

L. B. TYNG.
